UNITED STATES PATENT OFFICE.

BRUNO KNOBLOCH, OF APOLDA, GERMANY.

KNOCKING OVER BITS OF WARP MACHINES AND HOSIERY MACHINES AND THE LIKE.

Application filed June 5, 1922, Serial No. 566,097, and in Germany November 19, 1921.

The invention relates to improvements in the knocking over bits of warp machines and hosiery machines, and more particularly it consists in the arrangement of needle guiding channels at the free ends of the blades of knocking over bits.

The so-called knocking over bit, which is used in certain types of warp-machines and hosiery machines, consists in a number of parallel blades, which are fastened at their one sides in a lead block, while at their other free ends, between which the needles or the sinkers or the like are reciprocating up and down, a wire or rod is provided near the extremity of the blades, which wire serves as a support for the needles against the lateral pressure of the presser-bar. However it has been found to be a short-coming of those machines, that the needles are supported only at a mere point by the wire crossing the ends of the knocking over blades, and further the blades themselves work often irregularly in stripping off the meshes or loops of the fabric from the needles, for the reason that the blades must be arranged in some distance from each other, to allow for the working vibrations of the needles reciprocating between them.

But warp-machines and hosiery machines, which are built according to the present invention, may be run with considerably greater speed, so as to turn out a much greater output, because the new and improved construction of the knocking over bit provides for a much better guidance of the reciprocating needles, and secures a more accurate stripping off from the needles of the meshes or loops of the fabric. Another important feature of the new construction consists therein, that the needles are supported on a greater part of their length against the lateral pressure of the presser-bar. These advantages are obtained according to the invention by providing the free ends of the blades in knocking over bits with loops, with U-formed shoes, or with oblong eyes, in which the reciprocating needles are guided very close at both sides and in comparatively long guiding channels and are guided likewise at the third side in the direction of the pressure of the presser-bar.

In the drawing Fig. 1 is a section through a knocking over bit, in which the free end of each blade bears a U-shaped needle-guide;

Fig. 2 is a plan of the right hand half of Fig. 1; Figs. 3 and 4 correspond to the Figs. 1 and 2 and illustrate a modification, in which the free end of the blade bears an oblong narrow channel; Figs. 5 and 6 are plan views of other modifications, in which the end of the blade is formed into a narrow loop; Figs. 7 and 8 are a section and a plan view of another modification, in which each blade is transformed into a long narrow loop or eye; Figs. 9 and 10 are a longitudinal section and a plan of two other modifications with lug-shaped ends at the upright blades.

The embodiment of the invention shown in the Figs. 1 and 2 consists in a bent check plate or body *a* to which a number of knocking over blades *c* are secured by the means of the solder *b* or in some other convenient way. The free end of each blade is provided with a U-shaped shoe *i*, formed preferably by a correspondingly bent piece of metal.

In the embodiment according to Figs. 3 and 4, instead of the U-shaped shoe an oblong narrow channel *k* is fastened at the end of the blade or shaft *c'*, which channel-like piece *k* may be obtained by cutting a ring from a metallic tube and pressing it flat into the shown form of the narrow channel-piece.

Another suitable form of needle-guiding knocking over bits with the improvement of the present invention is obtained according to Figs. 5 and 6 bending the blades or shafts *c'* at their free ends in a narrow turn, so as to form a prolonged hook or loop *l*. The stability of this hook or loop *l* is improved, of the blade or shaft *c'* bent also at *l'* (see Fig. 6) which brings the axis of the shaft in line with the axis of the hook or loop *l*.

In the embodiment of the Figs. 7 and 8 also U-shaped or looped needle-guides are fixed to the check-plate or body *a'* by means of the solder *b'*, which needle-guides are formed however by bending correspondingly cut pieces of sheet-metal, so as to form an oblong eye *m*, the two shank ends *c'* of each eye being prolonged on to the body or check-plate *a'*.

The form of construction illustrated in the Figs. 7 and 8 is distinguished also by the feature that the needle-guiding parts *m* of the knocking over bit extend upwards from the body plate *a'* and the solder *b'*, whereby the working parts of the machine are ren-

dered more surveyable and better accessible, which is important in the case of stoppages or breakdowns in operation or in the case of other disturbances of the service.

- 5 All knocking over bits with U-shaped, eye-formed or looped needle-guides as up to now described (Figs. 1 to 8) are of the type adapted to work at the outer side of the needle bars. If they are to work at the inner sides of the needle bars, or between these bars respectively, the closed or the open needle guiding parts of the knocking over bit are arranged with their respective shanks in the manner illustrated in the Figs. 9 and 10. On the left hand side of these figures oblong ring-shaped needle-guides k' similar to those of Figs. 3 and 4 are attached to the shanks a'' by the solder metal b'' ; and on the right-hand side U-shaped needle-guides i' similar to those of the Figs. 1 and 2 are secured to the shanks a'' in just the same manner.

I claim:

1. In knocking over bits for warp-machines and hosiery machines and the like, 25 the combination of a cheek-body, a number of parallel blades, fastened at the one side to the cheek-body, and U-shaped needle-guides provided at the ends of the blades opposite to the cheek-body. 30

2. In knocking over bits for warp-machines and hosiery machines and the like, the combination of a cheek-body, and a number of parallel blades each forming a U with prolonged shanks both shanks of which 35 blades are fastened to the cheek-body.

3. In knocking over bits for warp-machines and hosiery machines and the like, the combination of a cheek-body, and a number of parallel blades, forming U-shaped needle 40 guides, the blades being bent upwards from the plane of the cheek-body.

In testimony whereof I affix my signature.

BRUNO KNOBLÖCH.
